UNITED STATES PATENT OFFICE.

GUSTAV J. KNAACK AND CHARLES J. MARQUARDT, OF PRINCETON, WISCONSIN.

HEATING-DRUM.

1,213,212.

Specification of Letters Patent. Patented Jan. 23, 1917.

Application filed February 14, 1916. Serial No. 73,208.

To all whom it may concern:

Be it known that we, GUSTAV J. KNAACK and CHARLES J. MARQUARDT, citizens of the United States, residing at Princeton, in the 5 county of Green Lake, State of Wisconsin, have invented certain new and useful Improvements in Heating-Drums; and we do hereby declare the following to be a full, clear, and exact description of the invention, 10 such as will enable others skilled in the art to which it appertains to make and use the same.

The present invention is directed to improvements in heating drums, and has for 15 its object to construct a device of this character adapted for direct attachment to a heating stove.

A further object of the invention is to provide a drum so constructed and mounted 20 as to receive directly from the stove pipe the products of combustion, whereby the heat which usually escapes to the chimney is utilized for heating purposes.

A still further object of the invention is 25 to provide a drum attachment for heating stoves designed to utilize the waste heat and consequently reduce the consumption of fuel.

With these and other objects in view, this 30 invention resides in the novel features of construction, formation, combination and arrangement of parts to be hereinafter more fully described, claimed and illustrated in the accompanying drawing, in which:—

Figure 1 is a side elevation of the device, 35 showing the same in place on the stove. Fig. 2 is a rear elevation of the device. Fig. 3 is a top plan view. Fig. 4 is a sectional view on line 4—4 of Fig. 1. Fig. 5 is a sectional view on line 5—5 of Fig. 2. 40 Fig. 6 is a sectional view on line 6—6 of Fig. 1. Fig. 7 is a bottom plan view. Fig. 8 is a sectional view on line 8—8 of Fig. 3.

Referring to the drawing 1 indicates a 45 heating stove of conventional form, and 2 the drum, said drum having its inner and outer walls 3 and 4, respectively, curved, the latter wall being adapted to lie adjacent the body of the stove 1. The rear wall has secured thereto, and adjacent the lower end 50 thereof, angle brackets 5, said brackets having their arms 6 provided with slots 7 which are engaged by the clamping bolts 8, said bolts being also engaged in the slots 9 of the angle brackets 10, the arms 11 of which 55 being adapted to rest against the body of the stove, and at which time the forward edge

of the bottom 12 of the drum engages the fire pot skirting 13 of the stove. Since the angle brackets 10 are adjustable, it is obvious that the drum can be supported in a direct vertical position. 60

The crown 14 of the stove has connected thereto angle plates 15 which are engaged by the upper ends of the turn buckles 16, the lower ends of said turn buckles being 65 suitably connected to the wall 4 of the drum, said turn buckles serving to prevent the drum from tilting.

The top 17 of the drum has formed thereon flanges 18 and 19 which surround the 70 openings 20 and 21. The stove pipe 22, which leads from the combustion chamber of the stove, is connected to the flange 18, while the flange 19 is connected to the pipe, not shown, which leads to the chimney. 75

Having its ends connected to the front and rear walls 3 and 4 of the drum, is a plate 23, and having its lower edge connected to the plate is a deflecting plate 24, which extends from the wall 3 along the 80 edge of the plate 23 for substantially half the length thereof, as at 25, said plate terminating in a plate 26 which extends transversely of the plate 23 and is curved as at 27, and is thence extended for engagement 85 with the wall 4 of the drum, as clearly shown in Fig. 5 of the drawing. By providing the deflecting plate 24, flues 28 and 29 are provided, the flue 28 serving to receive the products of combustion from the pipe 22, while 90 the flue 29 directs the products of combustion to the chimney pipe.

Extending downwardly from the side edges of the plate 23 are baffle plates 30, which have their front and rear edges secured in any suitable manner to the walls 3 and 4 respectively, the lower ends of said plates stopping at a point above the bottom 12 of the drum. 95

An intermediate baffle plate 31 is provided and extends upwardly from the bottom 12 of the drum and between the baffle plates 30, thereby providing a circuitous passage, as clearly shown in Fig. 6 of the drawing, since the upper edge of the baffle 105 plate 30 is spaced below the plate 23. The bottom 12 is provided with an opening 32 on each side of the baffle plate 31, said openings being normally closed by doors 33, which operate in the guides 34, whereby 110 said doors can be readily removed so that the drum can be cleaned.

From the foregoing description it will be seen that the products of combustion will first enter the flue 28, and will thence pass down between the adjacent side wall 35 of the drum and baffle plate 30, and thence under the baffle plate and over the baffle plate 31, where it will continue downwardly and under the lower edge of the other baffle plate 30, and thence upwardly to the flue 29 where it will be free to escape through the chimney pipe after being utilized to heat the drum.

What is claimed is:—

A heating drum, means for detachably and adjustably connecting the drum to a stove, said drum having a horizontal plate extended from its front to its rear wall and spaced from the side walls of the drum and top of the drum, a deflecting plate extending from the front wall to the rear wall and having a part disposed transversely between the plate and top of the drum to provide inde-

pendent flues, baffle plates depending from the side edges of the plate and having their lower edges spaced from the bottom of the drum, an intermediate baffle plate having its lower edge connected to the bottom of the drum and its upper edge disposed above the lower edges of the first named baffle plates, and a pipe leading from the stove to one of the flues for directing the products of combustion into the adjacent flue, whereby the products of combustion will pass around the baffle plates and to the remaining flue, as and for the purpose set forth.

In testimony whereof, we affix our signatures, in the presence of two witnesses.

GUSTAV J. KNAACK.
CHARLES J. MARQUARDT.
